UNITED STATES PATENT OFFICE.

MORITZ NEUGASS, OF NEW YORK, N. Y.

DESIGN FOR A HAT OR CAP.

SPECIFICATION forming part of Design No. 21,325, dated February 2, 1892.

Application filed December 18, 1891. Serial No. 415,547. Term of patent 3½ years.

To all whom it may concern:

Be it known that I, MORITZ NEUGASS, a citizen of the United States, residing at New York, in the county and State of New York, have 5 invented and produced a new and original Design for Hats and Caps, of which the following is a specification, reference being had to the accompanying drawings, forming part thereof.

Figure 1 is a perspective view of the design, and Fig. 2 is a sectional side elevation of the same.

The leading feature of the design consists

of a circular top A, surrounded at its edge by a ring B. The side C is circular and inclined 15 inwardly and downwardly from the ring B to terminate at the lower edge in a band D. The center of the top A may be embellished by a bow, button, or other ornament.

I claim—

The design for hats and caps, herein shown and described.

MORITZ NEUGASS.
